(57) **CLAIM**

The ornamental design for the outlet box assembly, as shown and described.

DESCRIPTION

FIG. 1 is a top perspective view of an outlet box assembly of the present invention.

FIG. 2 is a first side perspective view of the outlet box assembly of FIG. 1.

FIG. 3 is a second side perspective view of the outlet box assembly FIG. 1.

FIG. 4 is an elevational first end view of the outlet box assembly FIG. 1.

FIG. 5 is an elevational second end view of the outlet box assembly of FIG. 1.

FIG. 6 is elevational first side view of the outlet box assembly of FIG. 1.

FIG. 7 is elevational second side view of the outlet box assembly of FIG. 1.

FIG. 8 is top plan view of the outlet box assembly of FIG. 1; and,

FIG. 9 is a bottom plan view of the outlet box assembly of FIG. 1.

The features shown in broken lines are for exemplary purposes only and form no part of the claimed invention.
